UNITED STATES PATENT OFFICE.

MICHAEL HANKULICH, OF WEBSTER, PENNSYLVANIA.

THIEF-CATCHING DEVICE FOR BANKS.

1,181,307.

Specification of Letters Patent.

Patented May 2, 1916.

Application filed January 10, 1916. Serial No. 71,265.

To all whom it may concern:

Be it known that I, MICHAEL HANKULICH, a citizen of the United States of America, residing at Webster, in the county of Westmoreland and State of Pennsylvania, have invented certain new and useful Improvements in Thief-Catching Devices for Banks, of which the following is a specification.

This invention relates to new and useful improvements in thief catching devices for banks.

The primary object of the invention is the provision of a means for capturing any persons who are standing at the cash windows 15 of a bank, such for instance as a thief wrongly demanding money, the device being arranged for automatically sounding the alarm at a distant point.

A further object of the device is to provide a means for capturing persons attempting to hold up a bank and retain such persons adjacent the money windows of the bank and being readily operated by the bank officials, an electric alarm being automatically sounded at a distant police station when the device is operated.

The invention is adapted to be readily installed in connection with the money windows of any bank for preventing "hold ups" 30 which frequently occur in different localities, the device being in the form of shiftable partitions automatically operated upon being released and arranged to close an electrical circuit for sounding an alarm at any 35 distant point such as within the police station.

With these general objects in view and others that will appear as the nature of the invention is better understood, the same consists in the novel combination and arrangement of parts hereinafter fully described, 40 illustrated in the accompanying drawings and then claimed.

In the drawings forming a part of this 45 application and in which like designating characters refer to corresponding parts throughout the several views:—Figure 1 is a horizontal sectional view through a bank provided with the present device. Fig. 2 is 50 a similar enlarged sectional view through one of the guides for the shiftable partition when the latter is open. Fig. 3 is a similar view with the partition closed. Fig. 4 is a detail sectional view through the device, 55 parts being broken away with the partition retained in its open position. Fig. 5 is a

similar view with the partition released and closed. Fig. 6 is a perspective view of the upper portion of three of the partition panels. Fig. 7 shows detail views of the 60 antifriction members carried by the panels, and Fig. 8 is a detail view partially in section of the retaining catch for the partition and the alarm switch.

It being understood that the invention 65 may be employed in connection with the paying window of any bank, the same is herein illustrated in connection with a bank having side walls 10 and a safe deposit vault 11 and with cages 12 for the officials of the 70 bank such as the cashier and paying teller.

The front wall or casing 13 of the cages 12 is provided with the usual windows or openings 14 for dispensing money therethrough to customers within the space 15 75 forwardly of the said wall. Substantially semi-circular guides 16 and 17 are provided adjacent the wall 13 and positioned respectively above and below each of the openings 14, the said guides being channel-shaped in 80 cross section and the lower guide 17 being preferably countersunk within the concrete or other form of floor 18 with which the bank is provided. A flexible partition 19 is formed of a plurality of panels 20 hinged 85 together as at 21 and slidably arranged within the guides 16 and 17 and adapted for sliding therein as well as for reception within passages 22 in the adjacent sides of the said wall 13, the partition 19 being so 90 formed as to slide through the guides 16 and 17 and into and out of the opposite passages 22. Anti-friction balls 23 are carried by the lower edges of each of the panels 20, while similar ball members 24 are revolu-

bly journaled in the panels 20 at points adjacent the upper and lower ends thereof. For this arrangement it will be understood that the balls 23 and the lower balls 24 are arranged within the lower guide 17 while the upper balls 24 are positioned within the upper guide 16 and whereby the sliding partition is anti-frictionally mounted for opening and closing forwardly of the adjacent window 14.

Coil springs 25 are positioned in the passage 22 at one side of each of the windows 14 and have their outer ends anchored within the said passages while their opposite ends are attached to the adjacent end of the 110 partition 19, the partition being normally positioned within the passage 22 at the op-

posite side of the window 14 from that in which the springs 25 are secured. The said springs are thus normally tensioned in their extended positions within the guides 16 and 17 as best illustrated in Figs. 2 and 4 of the drawings.

Retaining latches 26 are slidably positioned between the upper and lower guides 16 and 17 and are operatively connected to 10 a shiftable lever 27 positioned within the adjacent cage 12 at any desired point, a spring 28 normally maintaining the latches 26 inwardly projected in seating retaining engagement with the adjacent end panel 20 15 of the partition.

With the partition 19 in its set arrangement as illustrated in Figs. 2 and 4 of the drawings and with the springs 25 under tension, an upward movement of the lever 20 27 releases the latches 26 and allows the springs 25 to forcibly and quickly slide the partition 19 out of its receiving passage 22 and through the guides 16 and 17 and forming an inclosure forwardly of the window 25 14 for the purpose of retaining captive the person standing at the window, the partition being then arranged as illustrated in Figs. 3 and 5 of the drawings.

A spring pressed catch 29 is arranged in 30 the passage 22 wherein the springs 25 are anchored, the said catch being adapted to automatically engage the partition 19 when closed and retain the same until the catch 29 is released. When the said catch is re- 35 leased by a person within a room beneath the floor space 15, as in a cellar or other apartment, a cord 30 positioned wherever desired, such as in one of the passages 22 and secured to the adjacent end of the par- 40 tition 19 may be forcibly pulled for opening the said partition and drawing the same within the said passage 22, thus positioning the operating springs 25 under tension, the latches 26 being then engaged with the par- 45 tition 20 to releasably retain the partition open.

Space switch arms of any desired form are arranged adjacent the catch 29, one of the same being illustrated at 31 while cir- 50 cuit wires 32 connect the said switch with an alarm bell 33 positioned wherever desired and preferably within a distant police station, a source of electrical energy such as the battery 34 being placed in circuit with 55 the wires 32. The upper guide 16 is provided with a grating 35 inclosed thereby which forms the top of the inclosure made

by the partition 19 when operatively closed, thus preventing the thief from escaping over the top guide 16. It will thus be evident 60 that when the lever 27 is released for catching the thief within the sliding partition 19, the adjacent metallic panel 20 will contact the switch members 31 thus closing the electrical circuit and automatically sounding the 65 alarm bell 33. The thief is thus captured within the bank by the officials thereof having operated the lever 27 and upon the sounding of the alarm bell 33 persons such as policemen who are thus made aware of 70 the capture may assemble in the bank and force the thief to submit himself to legal arrest.

While the form of the invention herein shown and described is what is believed to 75 be the preferable embodiment thereof, it is nevertheless to be understood that minor changes may be made in the form, proportion and details of construction without departing from the spirit and scope of the in- 80 vention as hereinafter claimed.

What I claim as new is:—

1. A device of the class described comprising in combination with a bank cage having a window therein and being further provided with passages at opposite sides of the window, substantially semi-circular U-shaped guides arranged above and below the window, a partition formed of panels hinged together shiftable arranged within the said guides and slidably within the said opposite passages, releasable retaining latches for the said partition, and automatic closing springs operatively attached to the said partition. 85

2. A device of the class described comprising in combination with a bank cage having a window therein and being further provided with passages at opposite sides of the window, substantially semi-circular U-shaped guides arranged above and below 90 the window, a partition formed of panels hinged together shiftable arranged within the said guides and slidably within the said opposite passages, releasable retaining latches for the said partition, closing springs 95 for the said partition arranged within the said guides and having their outer ends anchored within one of the said passages, a retaining catch for the said partition and an opening pull cord arranged within the other 100 one of the said passages and attached to the adjacent end of the partition. 110

In testimony whereof I affix my signature.
MICHAEL HANKULICH.
